US00D975845S

(12) **United States Design Patent** (10) **Patent No.:** **US D975,845 S**
(45) **Date of Patent:** **** Jan. 17, 2023**

(54) **MEDICINE ADMINISTRATION DEVICE**

(71) Applicants: **HIROSAKI UNIVERSITY**, Aomori (JP); **OTSUKA PHARMACEUTICAL FACTORY, INC.**, Naruto (JP)

(72) Inventors: **Tadashi Kobayashi**, Aomori (JP); **Hiroki Maita**, Aomori (JP); **Hiroyuki Kato**, Aomori (JP); **Takashi Akimoto**, Aomori (JP); **Takehito Hayashi**, Naruto (JP); **Koichi Takeda**, Naruto (JP); **Toshimitsu Terao**, Naruto (JP); **Tomoki Morita**, Naruto (JP); **Shinichiro Ito**, Naruto (JP); **Tadashi Komuro**, Ibaraki (JP); **Teruyuki Iwama**, Ibaraki (JP)

(73) Assignees: **HIROSAKI UNIVERSITY**, Aomori (JP); **OTSUKA PHARMACEUTICAL FACTORY, INC.**, Tokushima (JP)

(**) Term: **15 Years**

(21) Appl. No.: **29/764,255**

(22) Filed: **Dec. 29, 2020**

(30) **Foreign Application Priority Data**

Jul. 1, 2020 (JP) 2020-013458

(57) **CLAIM**

The ornamental design for a medicine administration device, as shown and described.

DESCRIPTION

FIG. 1 is a perspective 1 view of an embodiment of a medicine administration device showing our new design; FIG. 2 is a perspective 2 view thereof;

FIG. 3 is a front view thereof;

FIG. 4 is a back view thereof;

FIG. 5 is a top view thereof;

FIG. 6 is a bottom view thereof;

FIG. 7 is a right view thereof; the left view thereof being a symmetrical image;

FIG. 8 is a sectional view along the line shown in FIG. 4;

FIG. 9 is a right view shown in a usage state; and,

FIG. 10 is another right view shown in a usage state, but without the bottom base for ease of illustration.

The broken lines in the drawings illustrate portions of the medicine administration device and form no part of the claimed design.

1 Claim, 5 Drawing Sheets
